US0D1027375S

(12) **United States Design Patent** (10) Patent No.: **US D1,027,375 S**
(45) Date of Patent: ** May 21, 2024

(54) **BREAST TISSUE ENHANCER**

(71) Applicant: **CINMAR, LLC**, Chesterfield, MO (US)

(72) Inventors: **Cynthia Somogye**, Chesterfield, MO (US); **Margaret Seeger**, Elsberry, MO (US); **Corey Feit**, St. Louis, MO (US); **Corry Blackburn**, St. Louis, MO (US); **Lauren Smith Bearden**, St. Charles, MO (US)

(73) Assignee: **CINMAR, LLC**, Chesterfield, MO (US)

(**) Term: **15 Years**

(21) Appl. No.: **29/805,591**

(22) Filed: **Aug. 27, 2021**

(51) LOC (14) Cl. **02-01**

(52) U.S. Cl.

USPC **D2/706**; D24/155

CLAIM

The ornamental design for a breast tissue enhancer, as shown and described.

DESCRIPTION

FIG. 1 is a perspective view of a first embodiment of a breast tissue enhancer in accordance with the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a breast tissue enhancer in accordance with the claimed design;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of a breast tissue enhancer in accordance with the claimed design;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of a fourth embodiment of a breast tissue enhancer in accordance with the claimed design;

FIG. 23 is a front view thereof;

FIG. 24 is a rear view thereof;

FIG. 25 is a right side view thereof;

FIG. 26 is a left side view thereof;

FIG. 27 is a top view thereof; and,

FIG. 28 is a bottom view thereof.

The broken line outline of the breast tissue enhancer depicts environment associated with the claim and forms no part of the claimed design.
